UNITED STATES PATENT OFFICE.

WARREN H. WALKER, OF RACINE, WISCONSIN, ASSIGNOR TO WALKER MANUFACTURING COMPANY, OF RACINE, WISCONSIN, A CORPORATION OF WISCONSIN.

COMBINED JACK HANDLE AND TIRE-LUG WRENCH.

Application filed July 6, 1926. Serial No. 120,772.

This invention relates to a combination tool, adapted to serve either as the operating handle for a lifting jack, or as a socket wrench for turning the nuts on the tire lugs.

5 In a preferred form of the invention, the device is made in two detachable sections which, when assembled, serve as the operating handle for the lifting jack, and when detached one of the sections serves as the 10 tire lug wrench.

The general object of the invention is to provide a single tool, as briefly described hereinabove, and as described in more detail hereinafter, which is capable of performing 15 the functions of both a lifting jack handle and a tire lug wrench.

Other objects and advantages of this invention will be more apparent from the following detailed descriptions of certain 20 approved forms of the invention.

In the accompanying drawings:

Fig. 1 is an elevation of the complete device in use as a jack-handle.

Fig. 2 is a similar view of the assembled 25 device, detached from the jack, the connection between the two sections of the device being shown in central longitudinal section.

Fig. 3 is an elevation of the detached 30 crank portion of the device.

Fig. 4 is an elevation of this portion of the device in use as a tire lug wrench, a portion of a tire, rim, and wheel being shown in transverse section.

Fig. 5 is an elevation of the extension 35 member, shown folded or collapsed for convenience in storage.

Fig. 6 is a transverse section, on an enlarged scale, taken substantially on the line 6-6 of Fig. 2.

Fig. 7 is an end view of one end of the 40 extension rod.

Fig. 8 is a side elevation of one end of this rod, the extreme end portion being shown in central longitudinal section to 45 illustrate the spring-detent mechanism.

Fig. 9 is a transverse section, on an enlarged scale, taken substantially on the line 9-9 of Fig. 2.

Fig. 10 is a side elevation of a simplified 50 form of extension rod.

Referring first to the drawings the jack-handle is formed of two detachable portions, one of which is in the form of a crank wrench quite similar to the ordinary tire-lug wrenches now in use. As shown in Figs. 3

and 4, this portion of the device may be formed of a continuous metal bar or rod, of preferably round cross-section, bent to form an operating crank or handle 1, connected by the right-angled portion 2 with the operating shaft 3. If desired, a rotatable sleeve or handle-grip 4 may be mounted on the shaft 3, but this feature is optional and may be omitted. At the end of shaft 3 is secured a wrench head 5 in which is formed 60 a socket 6 adapted to fit one of the nuts (usually hexagonal), which hold in place the lugs 7 for securing the rim 8 of tire 9 on a wheel, as partially illustrated at 10.

The head 5 is also formed with another 70 smaller socket extension 11, usually square in cross-section and substantially the same in form and dimensions as the socket in the end of the actuating stub-shaft 12 of the lifting jack. A typical lifting jack is shown in 75 Fig. 1, comprising a standard 13 and lifting screws 14, which are elevated or lowered by the driving gear or nut 15 driven by the beveled gear 16 on the inner end of stub-shaft 12. This jack is merely shown by way 80 of example, and this improved handle could be used with any lifting jack which is actuated by a rotatable or oscillatable shaft. Preferably, one or more recesses 17 are 85 formed in the sides of the sockets 11 in both the head 5 and the shaft 12 of the lifting jack. These recesses 17 are to be engaged by spring detents in the extension rod herein-after described.

When used as a lifting jack handle, an extension rod is provided adapted to form a continuation of the shaft 3, so that when the jack is located in operating position beneath the axle of a car, the crank 1 will extend out to an accessible position beyond the body of the machine. This extension member may be simply a continuous straight rod or bar 18, as shown in Fig. 10, conveniently made of round bar material, although the end portions 19 must be square or of other suitable 90 non-circular cross-section to fit the sockets 11 in the head 5 and shaft 12 of the lifting jack. Each head 19 is preferably beveled off at the end edges, as shown at 20, to facilitate the insertion of the rod end in the socket. A ball detent 21 is mounted loosely in a recess 22 formed in the end 19, and is urged 95 outwardly by a spring 23 to a partially projecting position in which it is held by the inturned walls 24 surrounding the entrance 100 105 110

to recess 22. One ball detent 21 may be used, or a pair of these detents may be urged in opposite directions by the same spring 23 confined therebetween, as shown in Fig. 8. 5 When the end 19 of the extension rod is forced into the socket 11, the balls 21 will give against the resistance of spring 23 and will subsequently snap into the recesses 17 to hold the head 19 yieldably within the 10 socket 11. It is not absolutely necessary that the socket 11 within the wrench head 5 be identical in form or size with the socket in the operating shaft 12 of the lifting jack, because the two ends 19 of the extension bar 15 18 could be suitably formed to fit the respective sockets. However, it is preferable to have these two sockets identical, and the ends 19 of the extension rod identical so that no care need be exercised in fitting the proper 20 head in the proper socket.

Instead of using a single continuous extension rod 18, as shown in Fig. 10, it is preferable, as illustrated in Figs. 2, 5 and 6 to divide this rod into two similar portions 25 25 and 26, the adjacent ends of which are pivoted at 27 within a clamp member 28. This clamp member 28 has its end portions crimped inwardly at 29 and 30 so as to hold the sections 25 and 26 in alinement when extended to the position shown in Figs. 2 and 6. 30 However, the crimped portions 30 will yield so that the members 25 and 26 may be folded inwardly to parallel positions, as indicated in Fig. 5, so that the device may be more 35 conveniently stored within the confines of a tool-box. Obviously, other means for either pivotally or detachably joining the sections of this rod may be used in place of the example here shown. Also, although the 40 spring detents 21 are a simple and preferable form of device for yieldably securing the extension rod in place, other equivalent detent means might be used.

It will be evident from Figs. 3 and 5 that 45 when the sections of this device are detached and collapsed they are of convenient size for storage in the tool box of the car. When only the tire lug wrench is required, the extension rod portion need not be used at all. 50 When the lifting jack is to be operated, the handle is easily assembled by simply folding out the rod sections 25 and 26 into alinement and inserting either end of this device

into the socket 11 in the wrench head 5. The handle is then attached to the jack in the usual manner. There is a considerable saving in initial cost since one crank portion serves both as the tire lug wrench and as the crank portion of the jack handle, and there is also a material economy in storage space and dead weight to be carried in the car.

I claim:

1. A lifting jack handle comprising an angular crank portion having an enlarged head at one end in which is formed a socket to engage the nut of a tire-lug, and also a socket extension similar to the handle receiving socket of a lifting jack and a detachable bar portion having its ends formed to engage the respective sockets in the head and lifting jack.

2. A lifting jack handle comprising an angular crank portion having an enlarged head at one end in which is formed a socket to engage the nut of a tire-lug, and also a socket extension similar to the handle receiving socket of a lifting jack, and a detachable bar portion having its ends formed to interchangeably engage the sockets in the head and lifting jack.

3. A lifting-jack handle comprising an angular crank portion having an enlarged head at one end in which is formed a socket to engage the nut of a tire-lug, and also a socket extension similar to the handle-receiving socket of a lifting jack, and a detachable bar portion formed of two similar bar members and a clamping member for pivotally connecting these members at one end, the free ends of the bar members being formed to engage the respective sockets in the head and lifting jack.

4. A lifting-jack handle comprising an angular crank portion having an enlarged head at one end in which is formed a socket to engage the nut of a tire-lug, and also a socket extension similar to the handle-receiving socket of a lifting jack, the socket extension having a detent receiving recess, a detachable bar portion having its ends formed to engage the respective sockets in the head and lifting jack, and yieldable detents in the ends of the bar portion adapted to engage the recesses in the sockets.

WARREN H. WALKER.
